UNITED STATES PATENT OFFICE.

GEORGE H. WHITE, OF CINCINNATI, OHIO.

COMBINED DOOR CHECK AND CLOSER.

1,126,148.

Specification of Letters Patent.

Patented Jan. 26, 1915.

Application filed January 2, 1914. Serial No. 809,975.

To all whom it may concern:

Be it known that I, GEORGE H. WHITE, a citizen of the United States, residing at Cincinnati, in the county of Hamilton and State of Ohio, have invented certain new and useful Improvements in Combined Door Checks and Closers, of which the following is a specification.

This invention relates generally to builders' hardware and particularly to that type of door hinges described and claimed in Letters Patent of the United States granted to me on the 26th of July, 1910, No. 965,265.

This invention is an improvement over that described in my application Ser. No. 602,261, allowed March 24, 1911.

The novel and useful features of the present invention will be hereinafter fully described and claimed, and illustrated in the accompanying drawings, in which—

Figure 1 is a side elevation of one hinge applied; Fig. 2 is an elevation of the butt member detached; Fig. 3 is a transverse section on the line 3—3 of Fig. 1; Fig. 4 is a vertical section; Fig. 5 is an elevation of the lap member; Fig. 6 is a view of the lower end of the butt member; Figs. 7 and 8 are views of detached details, and Fig. 9 is a transverse section on the line 9—9 of Fig. 4 with the spring omitted.

Throughout the following description and on the several figures of the drawings, similar parts are referred to by like reference characters.

Referring to the drawings for a specific description of the mechanism, 10 indicates a door or any other part of like nature adapted to swing laterally in either direction on a vertical axis determined by any desired number of hinges 11, by which the door may be secured to the stile 12. The hinge comprises two main parts,—the lap member 13 and the butt member 14, secured rigidly to the door and the stile. These parts are maintained in normal operative connection by a pair of plungers 15 and 16, which break joints with the aligned tubular portions of the butt and lap members. The plunger 15 may be withdrawn from the

butt by loosening and lifting upon a screw 15', in order to separate the butt and lap, and the plunger 16 may be withdrawn from the butt into the lower part of the lap by bearing down upon a screw 16', against the tension of the buffer spring 17.

To close the door automatically after the same has been opened in either direction I provide within the butt a strong coil spring 18 connected to a pair of blocks 19 and 20. Within the end of said spring adjacent the blocks are projections or studs 18^a, set into the respective blocks and each surrounded by a sleeve 18^b having a lip 18^c through which the end of the spring passes securing the sleeve against rotation on the projection 18^a. These projections and sleeves keep the spring from buckling and bearing against the inner wall of the butt member. The block 19 has a square pintle 19' extending upwardly through and fitted into a square hole in a finger plate or actuator 21, the upper portion of the pintle 19' being round at 19'' and terminating in a flat end 19^a, which upon being grasped by a pair of pliers the block 19 may be forced downward so as to bring the round part 19'' into the square actuator hole, permitting the block 19 to be turned in either direction to determine the proper or desired tension of the main spring 18, after which the portion 19' will again engage the actuator to maintain the said tension of the spring and the coöperation between the actuator and the block. The block 20 likewise has a pintle 20' coöoperating with the square hole in the actuator 22. The extremity of the pintle 20' is seated loosely in a rider or block 23 rigidly secured as by a screw 20'' in the lower part of the butt. Each actuator has a finger 24 coöoperating normally with a lug 24' or shoulder 25 formed in or on the face of the lap. Each finger 24 also bears against the shoulder 24' at the end of a slot 26 in the butt. These parts are arranged oppositely in pairs. When the door is swung open in either direction one finger bears against its shoulder 25, and the spring is put under tension thereby, the other actua-

tor finger at such time being held against its butt shoulder 24'. Anti-friction rollers or balls 27 are shown between the bearing surfaces of the butt and lap, and in some 5 instances it may be found advantageous to employ removable keys at 21^a to secure the actuators rigidly to the block pintles.

An important feature of this invention consists in combining with and within the 10 hinge buffer means to control movement of the door and to provide a means to hold the door against undesired open swinging. This controller or buffer comprises the spring 17 supporting the plunger 16 and 15 resting upon a seat 28. Said seat may be provided on its upper surface with a lug 28^a to center the spring 17, and is adjustable up or down within the lap to vary the tension of the buffer spring, by means of a 20 threaded lug 28' upon which operates a nut 28'', and to which access may be had through a slot 28^b. The nut 28'' is supported upon a fixed abutment 29, and the seat 28 is prevented from rotation by a feather 28^c extending into the body of the lap. See Fig. 9. The plunger 16 on its upper end has a lug or projection 16'' which co-operates with a cam 23' on the lower end of the rider 23, and is normally seated in the socket 23'' of 30 said cam, preventing the door from freely 35 oscillating or swinging on its hinges. When the door is closing under the force of the main spring 18 it will be checked as it approaches its closed position, by contact of the lug 16'' and the cam 23', the effect of 40 such action being determined by adjustment of the spring 17. A plurality of projections 16'' and cams 23, may be employed if desired. The plunger 16 includes a thimble 16^a which breaks joints with the butt and lap and within which thimble the buffer portion 16^b of the plunger is free to slide 45 vertically. The screw 16' normally secures the thimble 16^a from movement.

45 The several parts of the device may be made of any suitable materials or relative sizes, and the details of construction may be varied to a considerable extent without departing from the spirit of the invention.

50 I claim:

1. In a device of the character set forth, the combination of a lap member and a butt member having aligned tubular portions, a pair of plungers normally breaking joints 55 between and pivotally connecting said members, said plungers being movable longitudinally into said lap member to disengage the butt member therefrom, a main spring within the butt member tending to maintain

60 said members in normal position, and buffer means to check the force of said spring, said buffer means including a portion of one of said plungers, a spring within one member resiliently supporting said plunger portion

at one end, and a rider carried by the other 65 member and having a cam co-operating with the other end of said buffer plunger portion.

2. In a device of the kind set forth, the combination of a lap member and a butt member, means pivotally connecting said members, said means including a plunger having at one end a lug projecting into one of said members and having its other end slidably and non-rotatably seated in the other of said members, a buffer spring supporting said plunger and resisting its 70 slideable movement, and a rider co-operating with the plunger at the end opposite the said spring and having a cam with a socket 75 adapted to receive said lug, for the purposes set forth.

3. The combination of a lap member having opposite facing shoulders, a butt member, pivot plungers connecting said members, a pair of actuators carried by the butt member and having projecting fingers, a main spring connected to the actuators and normally holding said fingers against said shoulders, a buffer rider within the butt member and having a cam co-operating with one of said pivot plungers; and a buffer spring seated in the lap member and resiliently supporting the just-mentioned plunger 90 in opposition to said rider, substantially as set forth.

4. In a device of the kind set forth, the combination of a lap member, a butt member, a pair of plungers pivotally connecting said lap and butt members, a spring to swing one of said members with relation to the 100 other thereof to normal position, buffer means within the hinge to control the force of said spring, one of said plungers constituting a part of said buffer means, and means on another part thereof to vary the 105 effect of the buffer on said spring.

5. In a combined door check and closer, the combination of a lap member and a butt member, means pivotally connecting said members, said means including a plunger 110 comprising a thimble breaking joints with the lap and butt members and a portion slideable within the thimble, a buffer spring supporting said slideable buffer portion at one end, and a rider co-operating with the 115 other end of said plunger portion, substantially as and for the purposes set forth.

6. In a device of the character set forth, the combination of lap and butt members, means pivotally securing said members together and permitting them to swing in either direction pivotally, and means normally resisting such swinging movement, the just-mentioned means comprising a pair of actuators within the butt member and 120 projecting therefrom into engagement with the lap member, a pair of blocks co-operating with said actuators, a coil spring be-

tween said blocks, a projection extending from each block into the adjacent end of the coil, and a sleeve surrounding each projection and having a lip, the adjacent end of the spring passing through said lip into the block and securing the sleeve from rotation upon the projection therein.

In testimony whereof I affix my signature in presence of two witnesses.

GEORGE H. WHITE.
